UNITED STATES PATENT OFFICE.

JOHN HERR, OF PHILADELPHIA, PENNSYLVANIA.

SCRUBBING MACHINE.

Application filed December 13, 1923. Serial No. 680,291.

To all whom it may concern:

Be it known that I, JOHN HERR, a citizen of the United States, and a resident of Philadelphia, in the county of Philadelphia and

5 State of Pennsylvania, have invented an Improvement in Scrubbing Machines, of which the following is a specification.

My invention relates broadly to machines for scrubbing floors and the like, but more 10 particularly to machines comprising means for supplying soap and water to the surface to be scrubbed in proximity to the scrubbing brush or brushes, as the case may be.

The general object of the invention is to 15 provide a machine of the character indicated of simple construction which is efficient in operation and which may be manufactured economically.

A further object of the invention is to 20 provide means whereby the movement of the machine over the surface to be washed effects distribution of the soap upon the said surface which combines with the water also distributed from the said machine to form a 25 washing and cleansing fluid.

Other objects and advantages of the invention will be pointed out in the detailed description thereof which follows or will be apparent from such description.

30 In order that the invention may be more readily understood, reference may be had to the accompanying drawings in which I have illustrated one convenient form of embodiment of the same. However, it will be understood that the invention is susceptible of embodiment in other forms of construction than that shown and that changes in the details of construction may be made within the scope of the claims without departing from 40 the said invention.

In the drawings,

Fig. 1 is a view in side elevation of a scrubbing machine embodying my invention;

45 Fig. 2 is a view in top plan of the said machine, portions thereof being broken away in order that other portions may be more clearly disclosed;

Fig. 3 is a horizontal sectional view of a 50 portion of the machine taken along the line 3-3 of Fig. 1;

Fig. 4 is a view showing a fragmentary portion of the structure for the purpose of illustrating more clearly certain details of 55 construction;

Fig. 5 is a view in elevation of a fragmen-

tary portion of the structure looking toward the right in Fig. 4;

Fig. 6 is a vertical sectional view taken 60 on the line 6-6 of Fig. 3; and

Fig. 7 is a horizontal sectional view of a fragmentary portion of the structure showing more clearly certain details of the construction.

Referring to the drawings, 1 designates 65 the frame portion or casing of a scrubbing machine upon the under side of which casing brushes 2 are rotatably mounted. The said brushes are rotated by means of gears, not shown, which are interposed between the 70 shaft of the electric motor 3 and the said brushes. The said motor is mounted upon the upper side of the supporting frame structure or casing 1 of the machine.

In view of the fact that the means for and 75 the manner in which the brushes 2 are supported and operated does not constitute any part of the invention as disclosed in this application, it is deemed unnecessary to describe the same in detail; but reference may 80 be had to my co-pending application filed December 13th, 1923, Serial Number 680,290, for a full disclosure and description of the same.

The motor 3 is provided with brackets 4 85 and 5 to which the frame 6 is adjustably secured by the bolts 7, the said frame having vertical slots therein to permit vertical adjustment thereof. The said frame is of hollow rectangular or square shape and supports a tank 10 which is adapted to hold water or a mixture of water and soap or other suitable detergent. The water or mixture of a detergent and water is adapted to be discharged from the said tank through a 90 pipe 11 controlled by a valve at 12. The said valve is provided with a crank arm 13 to which is connected a link 14 which in turn is connected to the lower end of swinging arm 15 pivoted at 17 to the lower portion of the 95 frame 6. The said arm 15 is provided with a curved slot 20 for a purpose which will be hereinafter described. The lower ends of the link 14 and the arm 15 are connected to the forward end of a link 25, the rear end 100 of which is connected to the forward end of a treadle lever 26 provided with a rearwardly extending projection or extension 27 adapted to be actuated by the foot. The valve at 12 is shown in closed position. By 105 depressing the rearwardly extending projection or extension 27, by placing the foot

thereon or otherwise, rotation of the valve 12 is effected to open the same. Rearward movement of the treadle lever 26 is adapted to be limited by contact of the forward end 5 thereof with an adjustable contact device 30' mounted upon the rear portion of the frame 6.

Simultaneously with the actuation of the valve at 12 to permit water to flow from the 10 tank 10 through the pipe 11, means is also actuated for permitting the discharge and distribution of soap or other detergent in powdered form onto the surface which is being washed at points adjacent the point of 15 discharge of the water from the pipe 11. The soap is contained within a receptacle 30 which is supported in the lower part of the frame 6 underneath the water tank 10. The front and rear walls of the said receptacle 20 30 are inclined downwardly toward each other, as shown in Figs. 1 and 6 of the drawings, and their lower edges are connected to the opposite edges of a flat bottom portion 31 which is provided with soap discharge holes 25 32 which are arranged at intervals longitudinally thereof. A valve member 33 consisting of an elongated flat bar is supported slidably underneath the bottom 31 by means of angular brackets 34. The said valve 30 member 33 is also provided with holes 35 at intervals therein which are adapted to be placed or moved into and out of registry with the holes 32 in the bottom 31 of the receptacle 30.

35 One end of the valve member 33 is extended and widened as shown at 40. The said widened end portion is provided with a slot 41 which is inclined with respect to the longitudinal axis of the said valve member 40 33. In other words, the slot 41 is arranged in a plane forming acute angles with the longitudinal axis of the said valve member. For the purpose of sliding the valve member 33 in one direction or the other, a link 45 is 45 provided, the rear end of which is connected to the treadle lever 26 by means of a thumb screw 46. The point of connection of the rear end of the link 45 to the treadle lever 26 may be adjusted from the position shown 50 to other positions, as for instance, to a position at 47 so as to vary the throw or movement of the said link 45 to thereby vary the extent of movement in one direction or the other imparted to the valve 33. Movement 55 of the said valve, by reason of the movement of the link 45, is effected by the engagement of a downwardly extending projection 50 at the forward end of the said link with the slot 41 previously referred to. The said projection 50 also extends through and engages a slot 60 formed in the outer edge portion of a projection or boss 61 upon the frame 6. The outer portion of the slot 60 is closed by a plate 62 held in place by screw bolts 63. 60 The slot 60 is arranged substantially at right

angles to the axis of the valve member 33 and it is apparent, therefore, that when the projection 50 is moved back and forth in the slots 41 and 60, the valve member 33 is caused to slide back and forth so as to open and close the openings 32 in the bottom 31 of the soap container. 70

The frame 6 and the portions carried thereby are supported upon a rotatable axle 70, the outer end portions of which are provided with wheels 71. The said frame portion is provided with ball bearings 73 by means of which the said frame is supported upon the said axle. The wheels 71 are secured rigidly to the said axle so that as the 80 apparatus is moved back and forth on the floor the wheels are caused to rotate and cause rotation of the shaft 70.

For the purpose of agitating the soap which is in powdered form within the container 30, I have mounted upon the shaft within the said container a coiled spring rod 75. The opposite end portions of the said coiled spring rod are coiled about drums 80 which are rigidly secured to the shaft 70 within the container 30 adjacent the opposite sides thereof. The coiling of the opposite end portions of the said spring 75 about the drums 80 maintains the said spring in cylindrical form. The opposite ends of the 90 said spring are secured to the drums 80 by means of screw bolts 81. Rotation of the axle 70 causes rotation of the drums 80 and of the spring 75. The convolutions of the coils are situated in close relation to the bottom 31 of the container or receptacle 30 and as the coil is rotated, the powdered soap or other detergent within the said container is agitated and is gradually moved longitudinally of the bottom across the openings 32 100 and is thereby caused to be discharged through the said openings. 105

When the soap and the water are being discharged onto the surface to be washed, it is desirable that the brush or brushes 2 110 should occupy a position intermediate the person who is operating the machine and the points of discharge of the soap and water. To this end the handle 90, which is of yoke shape and the opposite sides of which are pivotally connected at 17 to the opposite sides of the frame 6, is adapted to be turned from the position shown in full lines in Fig. 1 of the drawings into a position extending 115 toward the front of the machine, as indicated in dotted lines at 92. At such time a thumb screw bolt 93 provided in an extension of one of the sides of the handle engages the right hand end of the slot 20 in the arm 15 so as to swing the said arm toward the right (having reference to Fig. 1) and effect opening of the valve at 12 and also operate the links 25 and 45 to move the valve 33 into position to cause registry of the openings 35 therein with the openings 32 in 120 125 130

the bottom 31 of the receptacle or container 30. The soap and water having been discharged onto the surface to be washed is distributed by the brush or brushes 2 evenly 5 over the said surface in front of the person who may be operating the machine. It will be understood that at such time the operator pushes the machine rearwardly.

After the water and soap have been thus 10 mixed and distributed over the surface to be washed the handle may be returned from the dotted line position at 92 to the position indicated in full lines in Fig. 1 so that the operator may position himself at the rear 15 of the machine and push the same forward with the brush or brushes 2 in the lead or at the front of the machine. When the handle 90 is in the position shown in full lines in Fig. 1, the thumb screw bolt 93 may 20 be removed if desired; but preferably should be allowed to remain in place at all times as a matter of convenience.

A conductor 95 is provided for conveying 25 electric current to the motor. The flow of the current is controlled by a switch 96.

It will be seen that by my invention I have provided a machine of simple construction comprising means whereby the soap and water may be discharged onto a surface 30 to be washed and scrubbed and thereafter distributed over such surface by brushes which may be located or positioned intermediate the person operating the machine and the points of discharge of the soap and 35 water upon the said surface. It will also be seen that I have provided simple and efficient means for insuring that the proper amount of soap desired shall be discharged from the container or receptacle holding 40 the same; and it will also be apparent that if desired the link 45 may be disconnected from the valve bar 33 so that the latter may remain closed when the valve at 12 is open. This may be the case when a mixture of a 45 detergent and water is employed in the tank 10.

Having thus described my invention, what I claim and desire to secure by Letters Patent is:

50 1. In a scrubbing machine comprising scrubbing brushes and means for actuating the same, the combination of a frame, a water tank supported on said frame, a soap holding receptacle also supported on the 55 said frame, means for controlling the flow of water from said tank, means for controlling the discharge of soap from said receptacle, and means common to the last two named means for actuating the same to regulate and control the discharge of water and 60 soap onto the surface to be washed.

2. In a scrubbing machine comprising a scrubbing brush and means for operating the same, the combination of a water tank, 65 a receptacle for holding soap, means for

supporting said tank and receptacle, means for controlling the discharge of water onto a surface to be washed, means for controlling the discharge of soap onto said surface, an actuating member, and means having connection with said member and with the last two mentioned means whereby the latter are adapted to be actuated upon the actuation of the said actuating member.

3. In a scrubbing machine, the combination of a water holding tank, a detergent holding receptacle having discharge openings in its bottom, means for supporting the said tank and receptacle, which means comprises a shaft which extends through the said receptacle, a valve member for controlling the openings through the bottom of said receptacle, a valve for controlling the discharge of water from the said tank, a single means which is adapted to be actuated to actuate the said valves and means having connection with the said shaft and being situated within the said receptacle for agitating the detergent within the said receptacle for causing its discharge through the 90 said openings.

4. In a scrubbing machine comprising scrubbing brushes and means for operating the same, the combination of water and detergent holding receptacles, the said detergent holding receptacle being provided with discharge openings arranged at intervals in the bottom thereof, a discharge passageway leading from the said water holding receptacle, a valve for controlling the water discharge passageway, a valve member for controlling the openings from the said soap receptacle, a valve actuating member and a link connection between the said member and the valve for controlling the water passageway and a link connection between the said member and the valve member for controlling the soap discharge passageway, the said links operating simultaneously upon the actuation of the said actuating member for 100 opening or closing the said valve members.

5. In a scrubbing machine comprising scrubbing brushes and means for actuating the same, the combination of a water holding receptacle having a water discharge passageway leading therefrom, a detergent holding receptacle having discharge openings in the bottom thereof arranged at intervals, a valve for controlling the discharge of water from the said tank through the 115 said passageway, an elongated valve member located upon the bottom of the said detergent receptacle, means for opening and closing the first named valve and means for simultaneously effecting longitudinal movement of the said valve member for effecting the opening and closing of the openings in the bottom of the detergent holding receptacle, substantially as described.

6. In a scrubbing machine comprising 130

- scrubbing brushes and means for actuating the same, the combination of a water holding tank having a discharge passageway leading therefrom, a detergent holding receptacle situated underneath the said tank, the said receptacle being provided with openings arranged at intervals in its underside, an elongated member extending into the said receptacle and located in contact with the underside of the same over the said openings, a treadle lever and independent connections between the said lever and the said valves whereby the said valves may be simultaneously actuated.
7. In a scrubbing machine comprising a scrubbing brush and means for operating the same, the combination of a water holding tank having a passageway for the discharge of water therefrom, a detergent holding receptacle underneath the said water tank, the said receptacle having a series of discharge openings arranged at intervals through its under sides, a valve for controlling the discharge of water through the said passageway, a bar extending into the said receptacle which bar is provided with a series of openings arranged at intervals and which is located in contact with the underside of said receptacle over the openings through the underside of the latter, means for effecting simultaneous actuation of the said valve and the said bar for controlling the discharge of water through the said passageway and for controlling the discharge of the detergent through the openings in the underside of the said receptacle, a helical member located within the said receptacle, the spirals of which are situated adjacent the said bar and means causing rotation of the said helical member when the said machine is moved over the surface being scrubbed.
8. In a scrubbing machine comprising a scrubbing brush and means for operating the same, the combination of a water holding tank having a passageway for the discharge of water therefrom, a detergent holding receptacle underneath the said water tank, the said receptacle having a series of discharge openings arranged at intervals through its underside, a valve for controlling the discharge of water through the said passageway, a bar extending into the said receptacle which bar is provided with a series of openings arranged at intervals and which is located in contact with the underside of said receptacle over the openings through the underside of the latter, means for effecting simultaneous actuation of the said valve and the said bar for controlling the discharge of water through the said passageway and for controlling the discharge of the detergent through the openings in the underside of the said receptacle, a helical member lo-

cated within the said receptacle, the spirals of which are situated adjacent the said bar, means for supporting the said helical member and maintaining it in cylindrical form, and means for causing rotation of the said support and the said helical member for agitating the detergent within the said receptacle when the said machine is moved over the surface which is being scrubbed.

9. In a scrubbing machine comprising scrubbing brushes and means for operating the same, the combination of a water tank having a water discharge passageway leading therefrom, a detergent holding receptacle having openings arranged at intervals in its bottom, a valve for controlling the discharge of water through the said conduit, a valve bar extending into the said receptacle and being situated in contact with the bottom thereof over the said openings, which bar is provided with a series of openings arranged at intervals which are adapted to be moved into and out of registry with the openings in the bottom of said receptacle, means for simultaneously actuating the said valve and said valve bar to move the same into open or closed positions, and means whereby the said valve bar may be disconnected from the last mentioned means to permit the said bar to remain in closed position, substantially as described.

10. In a scrubbing machine comprising scrubbing brushes and means for operating the same, the combination of a water holding tank having a discharge passageway leading therefrom, a detergent holding receptacle having a series of openings arranged at intervals in the bottom thereof, a valve for controlling the passageway from the said tank, a reciprocable bar extending into said receptacle which bar is located in contact with the said bottom over the said openings therein and which is provided with a series of openings which are adapted to be moved into and out of registry with the openings in the said bottom, means for operating the said valve and the said bar for controlling the said passageway and the first named openings, and means for controlling the extent of movement of the said bar, substantially as described.

11. In a scrubbing machine comprising scrubbing brushes and means for actuating the same, the combination of a water holding tank having a discharge passageway leading therefrom, a detergent holding receptacle situated underneath the said tank, the said receptacle being provided with openings arranged at intervals in its underside, an elongated valve member extending into the said receptacle and located in contact with the underside of the same over the said openings, means for actuating the first named valve to open and close the

same, means for causing longitudinal movements in one direction or the other of the said elongated valve member to effect opening and closing of the openings in the 5 under side of the said receptacle, the said means comprising a treadle lever and independent connections between the said lever and the said valve and valve member

whereby they may be simultaneously actuated.

In testimony that I claim the foregoing as my invention, I have hereunto signed my name this 12th day of December, A. D., 1923.

JOHN HERR.
